FISH LURE

Jack H. Masters, 1053 Riverside Drive,
Battle Creek, Mich. 49015

Filed Feb. 2, 1970, Ser. No. 21,193

Term of patent 14 years

Int. Cl. D22—05

U.S. Cl. D22—27

FIG. 1

FIG. 2

FIG. 3

FIG. 1 is a side view of a fish lure, the other side having the same appearance.

FIG. 2 is a top view thereof, and

FIG. 3 is a bottom view thereof.

The broken lines indicating a conventional trailing hook assembly and towing assembly attached to the ends of the fishing lure, are for illustrative purposes only.

I claim:

The ornamental design for a fish lure, substantially as shown and described.
